UNITED STATES PATENT OFFICE.

KOSTA R. MILOVANOVITCH-KOKA, OF VIENNA, AUSTRIA-HUNGARY.

CARTRIDGE-FEED CASE FOR MAGAZINE-GUNS.

SPECIFICATION forming part of Letters Patent No. 447,577, dated March 3, 1891.

Application filed September 27, 1890. Serial No. 366,320. (No model.) Patented in Belgium April 26, 1890, No. 90,331.

To all whom it may concern:

Be it known that I, KOSTA R. MILOVANOVITCH-KOKA, a subject of the King of Servia, residing at Vienna, in the Province of Lower Austria, in the Empire of Austria-Hungary, have invented certain new and useful Improvements in Cartridge-Holders, (for which I have obtained Letters Patent in Belgium, dated April 26, 1890, No. 90,331;) and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to cartridge holders or cases adapted to contain a number of cartridges for use with that class of magazine-guns in which the cartridges are supplied to the magazine from the top or from the bottom or from one or the other side, and more especially to that class of magazine-guns in which the magazine depends from the receiver, and in which the cartridges are introduced into said magazine through said receiver.

The invention has for its object to provide a cartridge-holder adapted to contain a number of cartridges sufficient to fill a magazine, to so construct the case that the contents thereof may be rapidly and readily expelled either at top or bottom, and so that one cartridge after another may be removed singly from the holder without danger of the remaining cartridges falling out, and in so constructing the holder as to be light yet sufficiently strong to protect the cartridges against injury.

To these ends the invention consists in structural features, as will now be fully described, reference being had to the accompanying drawings, in which—

Figure 1 is an elevation of a breech-loading magazine-gun with a portion of the receiver broken away to show the upper end of the magazine, and showing the cartridge-holder applied thereto in dotted lines. Fig. 2 is a perspective view, and Fig. 3 a side elevation, of a cartridge-holder constructed according to my invention.

The gun shown in Fig. 1 may be of any de-

sired or known construction, the magazine C depending from the receiver, which has a longitudinal slot in its bottom for the passage 55 of the cartridges to or from the magazine.

c' are the elastic stop-arms for retaining the uppermost cartridge from passing into the receiver under the stress of the feed-spring c. The stop-arms are forked and extend 6c along the mouth of the magazine from the rear end of the same, so that the uppermost cartridge will lie at an angle to the longitudinal axis of the receiver with the flange projecting into the path of the breech-bolt, as 65 shown, and as described in my said application.

The cartridge-holder D, Figs. 2 and 3, consists, essentially, of a sheet-metal casing having in horizontal cross-section the general 70 form of a cartridge, which casing is open at top and bottom. In the edges of the case, at top and bottom and near the ends thereof, are formed elastic lips d, diametrically opposite each other, which lips d are bent inwardly and serve to retain the cartridges in the holder. As shown, the sides of the case at the shell end are cut out to form openings d' of such dimensions as will readily admit of the use of the fingers for pushing the cartridges out when the holder is applied to the magazine, as shown in dotted lines in Fig. 1. These openings d' extend from one edge nearly to the opposite edge of the casing, but in reverse directions—that is to say, one of 75 the openings in one side of the casing extends from the upper edge nearly to the lower edge, and the like opening in the opposite side of the casing extends from the lower edge nearly to the upper edge thereof. Since 80 both the top and bottom of the casing are open it becomes reversible, so that either top or bottom can be presented to the magazine in replenishing the same, thereby avoiding 85 the necessity of taking cognizance of a top 80 and bottom, and facilitating the use of the holder accordingly. Inasmuch as the openings d' are comparatively large, having but a narrow strip of metal between them and the edge of the casing I preferably give to the 90 end of the openings a curvilinear form and corrugate the narrow strip of metal along the same, or form a curved outward bulge or rib by stamping, as shown at d'. Along the un-

slotted edge of each side of the case I form an outwardly-bent flange d' , extending from one elastic lip d to the other, that serves as a bearing for the holder, one or the other of said flanges resting upon the left edge of the mouth of the magazine when the holder is inserted into the receiver.

When the holder is in the position shown in dotted lines in Fig. 1, the cartridges therein can be readily pushed out of it, as all of them are exposed to the action of the fingers through the medium of the reversed slots d' in the sides of the casing, and the contents of the holder may be readily and rapidly ex-
15 pected, the elastic lips d yielding to pressure.

Having described my invention, what I claim is—

1. A cartridge holder or case consisting of a casing that is open at top and bottom and has finger-slots d' formed in the sides thereof at the shell end, said finger-slots d' extending

in reverse directions from one edge nearly to the opposite edge, in combination with retaining devices to prevent the cartridges from falling out, substantially as and for the purposes set forth. 25

2. A cartridge holder or case consisting of a sheet-metal casing that is open at top and bottom and that has inwardly-bent retaining-lips d formed on the side edges, and that has finger-slots d' formed in the sides at the shell end of the casing, which finger-slots extend in opposite directions from one edge nearly to the other, substantially as and for the purposes set forth. 30

In testimony whereof I affix my signature in presence of two witnesses. 35

KOSTA R. MILOVANOVITCH-KOKA.
